UNITED STATES PATENT OFFICE.

HENRY J. VAN VALKENBURGH AND DANIEL D. VAN VALKENBURGH, OF
RABBITT RIVER, MICHIGAN.

IMPROVEMENT IN CLOTHES-DRIERS.

Specification forming part of Letters Patent No. 131,483, dated September 17, 1872.

To all whom it may concern:

Be it known that we, H. J. VAN VALKENBURGH and D. D. VAN VALKENBURGH, of Rabbitt River, in the county of Allegan and State of Michigan, have invented a certain new and useful Improvement in Clothes-Driers; and we do hereby declare the following to be full, clear, and exact description thereof, reference being had to the accompanying drawing forming a part of the same, and in which—

Figure 1 represents a perspective view of our improved clothes-drier, and Fig. 2 a vertical section of the same with its upper part tilted or in an inclined position.

Similar letters of reference in the several figures refer to like parts.

This invention has reference to an improved clothes-drier, in which the post supporting the reel is made into two parts, hinged together, and supplied with means for properly retaining them in position when the reel is tilted or occupies a horizontal position, and in which the means employed in holding the parts of the reel in place upon the said post are of such a construction as to permit of the said reel being readily attached and detached when desired, substantially as hereinafter more fully described and claimed.

To enable others to make and use our invention, we will proceed to describe it.

In the annexed drawing, A refers to the post supporting the reel, and which is retained in an upright position by the feet or base pieces a a. This post is made into two parts, the lower one of which is recessed to receive the upper one of said parts, as shown in Figs. 1 and 2, and having the latter pivoted or hinged to it in such a manner as to permit of said latter part with its reel being tilted, whereby the said reel may be brought within such a distance of the operator as to allow of the articles to be dried being hung upon its upper part as readily as upon its lower lines. A staple or loop, b, is fastened to the lower or stationary part of the post A, and receives a wedge, b', when the upper part of the said post is in a vertical position for the purpose of retaining said upper part

in the said position; but when the said wedge is withdrawn the said upper part may be tilted or inclined and held in such position by the said staple, as plainly illustrated in Fig. 2. B B' refers to the reel, which consists of the horizontal bars B and inclined bars B', the inner ends of the former being hinged or pivoted within sockets formed in the cap C fitting upon the upper end of the post A, while the lower ends of the latter, the forward or upper ends of which are hinged or pivoted to and near the outer ends of the former, enter and rest within sockets constructed upon the ferrule C' embracing the post A, and resting upon a shoulder formed upon the latter. D is an annular plate or ring fitting around the post A, and held down upon the upper edges of the ferrule C' by means of a pin, or otherwise, for the purpose of assisting in retaining the bars B' in the sockets of the said ferrule. E is the line upon which the clothes to be dried are hung, and which is wound upon the reel B B' by inserting the knotted end thereof within the lower one of the double slots e e, and thence passing it around the reel, so as to enter the slots e' e', until it has been entirely strung upon said reel, (see Fig. 1,) when its end is fastened to one of the horizontal bars of the reel, as shown, putting it (the reel) in suitable condition to receive the articles for drying.

Having thus described our invention, what we claim, and desire to secure by Letters Patent, is—

1. The reel-post A, constructed as described, in combination with the staple b and wedge b', substantially as and for the purpose specified.
2. The cap C and ferrule C', in combination with the reel B B' and post A, constructed and arranged substantially as shown, and for the purpose set forth.

In testimony whereof we have hereunto signed our names in presence of two subscribing witnesses.

HENRY J. VAN VALKENBURGH.
DANIEL D. VAN VALKENBURGH.
